WATER IMPERVIOUS CLOSURE FOR
WASHING APPARATUS

Frank D. Low, La Grange Park, Ill., assignor to
General Electric Company, a corporation of
New York

Application October 29, 1949, Serial No. 124,360

3 Claims. (Cl. 134—183)

1

The present invention relates to washing apparatus, and more particularly to improved dishwashing apparatus of the general character of that disclosed in the copending application of Forrest A. Walker, Serial No. 57,448, filed October 30, 1948.

The dishwashing apparatus disclosed in the Walker application mentioned is of the timed washing cycle type that performs automatically and in predetermined sequence given steps including spraying, washing, rinsing and drying of the dishes and other utensils contained therein. This apparatus comprises a cabinet having a front opening and housing a vertically disposed vat including wall structure terminating in a forwardly directed doorway having a front opening registering with the first-mentioned front opening, and a door arranged in the doorway and mounted for movements with respect to the front openings between a substantially vertical closed position and a substantially horizontal open position. The wall structure of the vat and the door respectively carry cooperating baffles and are otherwise so constructed and arranged that hot washing fluid or liquid circulated in the vat does not escape between the doorway and the door out of the front openings, notwithstanding the absence of the usual sealing gasket therebetween.

While this gasketless door and doorway construction in the dishwashing apparatus of the Walker application is highly efficient and positive in operation, the structural form of the baffle that is carried by the inside wall of the door is subject to criticisms in that it projects considerably rearwardly therefrom when the door occupies its closed position and that it produces what may be termed a shearing action with the cooperating baffles that are carried by the walls of the vat as the door is moved into its closed position.

Accordingly, it is a general object of the present invention to provide washing apparatus of the front-opening gasketless-door type that employs an improved and simplified baffle arrangement for the purpose of preventing the escape of the washing liquid from the front opening.

Another object of the invention is to provide in washing apparatus including a vat having a forwardly directed doorway terminating in a front opening and a door mounted within the doorway for movements between open and closed positions with respect to the front opening, an improved arrangement of cooperating baffles respectively carried by the walls of the vat and by the inner wall of the door for preventing the escape of the washing liquid from the vat and without particu-

2

lar close fits and shearing action between the baffles as the door is moved into its closed position.

A further object of the invention is to provide in washing apparatus of the character noted, baffle structure that is so constructed and arranged that an improved turbulent action of the washing liquid is obtained within the vat adjacent to the doorway that is effective to limit the admission of washing liquid into the doorway from the vat.

Further features of the invention pertain to the particular arrangement of the elements of the washing apparatus, whereby the above-outlined and additional operating features thereof are attained.

The invention, both as to its organization and method of operation, together with further objects and advantages thereof, will best be understood by reference to the following specification taken in connection with the accompanying drawings, in which Figure 1 is a front elevational view, partly broken away, of dishwashing apparatus of the front-opening gasketless-door type embodying the present invention; Fig. 2 is a vertical sectional view, partly broken away, of the dishwashing apparatus, taken in the direction of the arrows along the line 2—2 in Fig. 1; Fig. 3 is a fragmentary horizontal sectional view of the front portion of the dishwashing apparatus, taken in the direction of the arrows along the offset line 3—3 in Fig. 2; Fig. 4 is a plan view of the inside of the front door of the dishwashing apparatus shown in Figs. 1 to 3, inclusive; Fig. 5 is a side elevational view of the front door shown in Fig. 4; and Fig. 6 is an enlarged fragmentary sectional view of one side of the inside of the front door, taken in the direction of the arrows along the line 6—6 in Fig. 4, and illustrating the substantially U-shaped cross section of the inverted substantially U-shaped baffle carried by the inside of the front door adjacent to the top and side flanges thereof.

Referring now to Figs. 1 to 3, inclusive, of the drawings, the dishwashing apparatus 10 there illustrated and embodying the features of the present invention is of the general construction and arrangement of that disclosed in the copending application of Edgar S. Stoddard, Serial No. 105,618, filed July 19, 1949, which dishwashing apparatus is of the front-opening gasketless-door type disclosed in the previously mentioned Walker application. The apparatus 10 comprises an outer casing or cabinet 11 provided with top and bottom walls 12 and 13, opposed side walls 14 and 15, and rear and front walls 16 and 17,

The bottom wall 13 has a plurality of downwardly depressed feet 18 formed therein for the purpose of spacing it from the supporting floor, or the like; and the front wall 17 is rearwardly offset adjacent to the bottom wall 13 in order to provide connecting substantially vertical and horizontal panels 19 and 20 adjacent to the front of the cabinet 11 so as to define a foot-receiving recess, permitting a person to work close to the front of the cabinet 11. Also, the front wall 17 has a front opening 21 formed in the upper portion thereof, the front opening 21 being offset toward the right; and a front panel 23 is carried by the front wall 17 and has a front opening 24 formed in the upper portion thereof, the front opening 24 being offset toward the right. The front opening 24 provided in the front panel 23 surrounds the front opening 21 provided in the front wall 17 and overlies a considerable marginal portion thereof adjacent to the lower portion of the front wall 17. The front panel 23 is provided with a rearwardly directed marginal flange 25 surrounding the front opening 24, and a rearwardly directed boundary flange 26, the top and side portions of the boundary flange 26 being respectively disposed substantially flush with the top wall 12 and with the side walls 14 and 15, and the bottom portion of the boundary flange 26 overlying the horizontal panel 20. The front panel 23 is suitably removably secured to the front wall 17 with the front openings 24 and 21 in substantial registry.

The cabinet 11 houses a substantially vertically disposed vat 27 arranged in the upper portion thereof and offset toward the right, the vat 27 comprising top and bottom walls 28 and 29, opposed side walls 30 and 31, and a rear wall 32. The top and bottom walls 28 and 29 and the side walls 30 and 31 terminate in a forwardly directed doorway 33 having a front opening 34 arranged in substantial registry with the front openings 21 and 24. More particularly, the top and side portions or flanges of the doorway 33 terminate in an outwardly and rearwardly rolled rim 35; while the bottom wall 29 is provided with a forwardly projecting flange 36 terminating in an upwardly and outwardly extending front ledge or lip 37 extending between the side flanges of the doorway 33, the front ledge 37 terminating adjacent to the front opening 34 of the doorway 33, whereby the upper edge of the front ledge 37 is disposed considerably above the bottom flange 36 and consequently the bottom wall 29. A substantially centrally disposed downwardly depressed sump 38 is formed in the bottom wall 29 and communicates with a downwardly embossed depression or groove 39 formed substantially centrally in the bottom flange 36 and extending forwardly toward the central portion of the front ledge 37. Further, an upstanding inverted substantially U-shaped inwardly embossed vat rib 40 is formed in the top wall 28 and in the side walls 30 and 31 at the junctions thereof with the corresponding flanges of the doorway 33, the vat rib 40 including downwardly extending legs 41 terminating just above the bottom flange 36 and well behind the front ledge 37.

The vat 27 is suitably supported within the cabinet 11 by the rear and front walls 16 and 17 thereof, and, in turn, carries a front door 42 that comprises an outer body sheet 43 terminating in an inverted substantially U-shaped rearwardly directed marginal flange 44, and an inner body sheet 45 terminating in an inverted substantially U-shaped rearwardly directed marginal flange 46.

The inner body sheet 45 is arranged in nested relation within the outer body sheet 43 and suitably secured in place so that the principal portions of the body sheets 43 and 45 are arranged in upwardly approaching spaced-apart relation. Further, the marginal flange 46 of the inner body sheet 45 is provided with an outwardly directed inverted substantially U-shaped marginal rim 47 that cooperates with the front surface of the associated vat rib 40 when the door 42 occupies its closed position. In order to retain the door 42 in its closed position a latch element 48 is secured to the central upper portion of the marginal flange 46 adjacent to the rim 47, the latch element 48 cooperating with a resilient latch element 49 secured within the upper central portion of the doorway 33.

The door 42 is mounted adjacent to the lower edge thereof within the doorway 33 rearwardly of and below the front ledge 37 by a hinge arrangement including two laterally spaced-apart substantially identical hinge mechanisms 50, whereby the lower ends of the outer and inner body sheets 43 and 45 are disposed in straddling relation with respect to the front ledge 37. Each of the hinge mechanisms 50 comprises complementary parts 51 and 52 respectively secured to the front surface of the inner body sheet 45 and to the flange 36, the hinge part 51 being disposed between the body sheets 43 and 45 and the hinge part 52 being disposed interiorly of the vat 27 and behind the front ledge 37. Also, each of the hinge mechanisms 50 comprises a bumper element 53 carried by the hinge part 51 and a cooperating bumper element 54 secured to the lower surface of the flange 36 exteriorly of the vat 27.

The hinge mechanisms 50 are not disclosed in detail, since they form no part of the present invention, and are disclosed in the copending application of Frank D. Low, Serial No. 61,633, filed November 23, 1948, now Patent No. 2,573,798, dated November 6, 1951. The hinge mechanisms 50 mount the door 42 within the doorway 33 for movements between a substantially vertical closed position and a substantially horizontally open position with respect to the front openings 21, 24 and 34. Also, it is noted that the door 42 may be completely removed from the doorway 33, when it occupies an intermediate position with respect to its open and closed positions, by virtue of the fact that the hinge parts 51 and 52 are disengageable. Further, when the door 42 occupies its open position the hinge parts 51 and 52 are suitably interlocked to prevent disengagement thereof, and the bumper elements 53 and 54 are engaged in order to support the weight of the door 42.

Further, a laterally extending and upwardly sloping bracing sheet 55 is arranged between the body sheets 43 and 45; and a handle 56 formed of plastic is suitably secured to the upper central portion of the door 42 adjacent to the top of the marginal flange 44 of the outer body sheet 43 in order to facilitate the movements thereof. For the purpose of ventilating the interior of the vat 27 an opening 57 is formed in the top of the marginal flange 44 of the outer body sheet 43 and receives a plastic element 58, the element 58 having a downwardly depressed basin 59 formed therein through which a number of spaced-apart laterally extending louver openings 60 are formed. Also, a plurality of laterally arranged holes 61 are formed in the top of the marginal flange 46 of the inner body sheet 45 and communicate with the louver openings

60. Accordingly, when the door 42 occupies its closed position the interior of the vat 27 is in communication with the top of the doorway 33 through the holes 61 and the louver openings 60 and consequently with the exterior, so that vapor given off by hot washing liquid in the vat 27 may be vented to the exterior. In order to prevent the vapor issuing from the top of the doorway 33 from condensing upon the front edge of a sink, or the like, not shown, disposed above the top wall 12, a laterally extending vapor directing or projecting element 62 formed of plastic is suitably secured to the front of the front panel 23 above the top of the doorway 33.

The construction of the elements 58 and 62 comprising the ventilating arrangement that is incorporated in the apparatus 10 have not been disclosed in detail, since this arrangement forms no part of the present invention, and is disclosed in the previously mentioned Stoddard application.

As best shown in Figs. 2 to 6, inclusive, the door 42 further comprises a plastic detergent cup 63 disposed in an opening provided in the inner body sheet 45 and opening toward the interior of the vat 27, as well as track structure for guiding a dish-carrying rack indicated generally at 64 in Fig. 3. Specifically, in the inner body sheet 45 a substantially centrally disposed trackway 65 is embossed and two side trackways 66 and 67 are provided that cooperate with rollers, not shown, carried on the lower portion of the rack structure 64 for the purpose of guiding the movements of the rack structure 64 over the door 42 in its open position. Specifically, the two side trackways 66 and 67 are carried by two side embosses 68 and 69 formed in the inner body sheet 45. The embosses 68 and 69 are directed inwardly and are provided with connected inwardly directing embosses 70 and 71 disposed in lateral alignment adjacent to the lower portion of the inner body sheet 45.

Also, an inverted substantially U-shaped flange or baffle 72 is carried within the marginal flange 46 of the inner body sheet 45 adjacent to the marginal rim 47 provided about the marginal flange 46. The baffle 72 is substantially Z-shaped in its principal cross section including inner and outer walls 73 and 74 and a connecting wall 75. Specifically, the outer wall 74 of the baffle 72 is directly secured by welding, or the like, to the inside surface of the marginal flange 46 of the inner body sheet 45 providing a space 76 between the inner wall 73 and the marginal flange 46. Thus the connecting wall 75 of the baffle 72 is disposed forwardly of the marginal rim 47 disposed about the marginal flange 46, while the inner wall 73 of the baffle 72 is disposed inwardly with respect to the marginal rim 47 and projects rearwardly with respect thereto. Finally, the extreme rear end of the inner wall 73 is provided with an inwardly rolled rim 77 in order to avoid any sharp edges. When the door 42 occupies its closed position, the inner wall 73 of the baffle 72 projects through the vat rib 40 and is spaced inwardly therefrom in order to prevent shearing action between the baffle 72 and the vat rib 40. Moreover, the baffle 72 cooperates with the vat rib 40 in order to define an inverted substantially U-shaped pocket 78 therebetween that is also substantially U-shaped in cross section, when the door 42 occupies its closed position. Also, two upstanding inwardly directed baffles 79 are embossed in the left-hand side wall 30 of the vat 27 adjacent to and rearwardly of the

the associated leg 41 of the vat rib 40; and two upstanding inwardly directed baffles 80 are embossed in the right-hand side wall 31 of the vat 27 adjacent to and rearwardly of the leg 41 of the vat rib 40. The two baffles 79 terminate adjacent to the lower ends thereof in a substantially horizontally disposed inwardly directed emboss 81 provided in the left-hand wall 30; and the two baffles 80 terminate adjacent to the lower ends thereof in a substantially horizontally disposed inwardly directed emboss 82 provided in the right side wall 31. The embosses 81 and 82 constitute trackways that cooperate with the rollers, not shown, that are carried by the lower portion of the rack structure 64 in order to support the rack structure 64 when it occupies its retracted position within the vat 27.

The details of the construction of the baffles 79 and 80 and the trackways 81 and 82 provided in the walls of the vat 27, the construction of the trackways 65, 66 and 67 carried by the door 42, and the construction of the rack structure 64 are not disclosed in detail, since they form no part of the present invention, and are disclosed in the previously mentioned Walker application. However, it will be understood that the rack structure 64 is movable through the doorway 33 into and out of the vat 27 when the door 42 occupies its open position. When the rack structure 64 is moved into its retracted position in the vat 27 it is supported upon the trackways 81 and 82; and when the rack structure 64 is moved into its extended position out of the vat 27 and over the door 42 it is supported upon the trackways 65, 66 and 67.

The apparatus 10 further comprises a bladed impeller 90 that is mounted upon a substantially vertically disposed operating shaft, not shown, of an electric motor 91 arranged below the sump 38. More particularly, the sump 38 is provided with an upwardly directed emboss, not shown, through which the shaft of the motor 91 projects and which is surrounded by the hub of the impeller 90. This arrangement permits ready rotation of the impeller 90 by the motor 91 and prevents escape of any substantial washing liquid from the vat 27. Specifically, the motor 91 is supported upon suitable brackets 92 secured to the lower portion of the sump 38; and an upstanding cylindrical reticulated screen 93 is removably arranged within the sump 38 about the impeller 90. Also, a liquid supply pipe 94 is arranged in the lower portion of the cabinet 11 below the vat 27 and is adapted to be connected to a source of cleansing or washing liquid, such, for example, as a hot water tank. The washing liquid is piped from the lower portion of the cabinet 11 upwardly between the rear wall 16 thereof and the rear wall 32 of the vat 27 by a flexible conduit 95 and into the top wall 28 of the vat 27. Specifically, a rotary spraying device 96 is arranged within an upwardly extending emboss 97 disposed substantially centrally in the top wall 28 so that the liquid may be sprayed downwardly through the rack structure 64 carried within the vat 27 and allowed to accumulate in the sump 38. The liquid supply pipe 94 is connected to an inlet valve mechanism 98 of the solenoid and dash-pot controlled type supported by the panel 20 and arranged to discharge into the conduit 95. The inlet valve mechanism 98 is normally biased into its closed position in order to cut off the supply of liquid from the liquid supply pipe 94 to the conduit 95, but is provided with an associated solenoid 99 that

is adapted, when energized, to operate the inlet valve mechanism 98 into its open position in order that washing liquid may be supplied from the liquid supply conduit 94 via the inlet valve mechanism 98, the conduit 95 and the spraying device 96 into the upper portion of the vat 27. Subsequently, when the solenoid 99 is de-energized, the inlet valve mechanism 98 is returned slowly to its closed position cutting off the communication between the liquid supply pipe 94 and the spraying device 96. The provision of the slow-closing inlet valve mechanism 98 eliminates water hammer in the plumbing preceding the liquid supply pipe 94.

Also, provided in the lower portion of the cabinet 11 is a drainpipe 100 that is connected through a suitable trap, not shown, to drain plumbing. The drainpipe 100 is carried by a drain fixture 101, that is, in turn, secured to the lower surface of the sump 38. The drain fixture 101 communicates with a flexible conduit 102, that, in turn, communicates with a drain fixture 103 that is secured within a drain opening provided in the lowermost portion of the sump 38. The drain fixtures 101 and 103 are formed of molded rubber, or the like; while the flexible conduit 102 comprises a section of rubber hose, or the like, that is internally reinforced to prevent collapse thereof. The drain fixture 103 frictionally engages the drain opening provided in the sump 38 and is restrained in position by a strainer 104. The flexible hose 102 comprises a portion of a drain mechanism 105 that further includes structure 106 that is secured to the side wall 30 adjacent to the bottom wall 29 of the vat 27. The structure 106 comprises a pair of spaced-apart guide elements 107 extending below the midsection of the hose 102, and a substantially S-shaped operating member 108 disposed between and cooperating with the guide element 107. The operating member 108 is pivotally mounted adjacent to the inner end thereof upon a pivot pin 109 carried by the structure 106 and is normally biased in the clockwise direction, as viewed in Fig. 1, by a coil spring 110 surrounding the pivot pin 109 and extending between the structure 106 and the operating member 108. The extreme outer end of the operating member 108 carries an upwardly extending projection 111 underhooking the midsection of the hose 102 and disposed between the outer surface of the hose 102 and the adjacent side wall 14 of the cabinet 11. Finally, the structure 106 carries an electro-responsive solenoid device 112 that is provided with a movable armature 113 which is operatively connected by a coil spring 114 to the extreme inner end of the operating member 108.

In view of the foregoing, it will be understood that the hose 102 extends in an arc between the drain fixtures 101 and 103 and that the midsection thereof is normally disposed below the drain opening provided in the sump 38 so that the drain fixtures 101 and 103 are in free communication with each other through the hose 102, whereby any wash liquid in the sump 38 may be readily drained into the drainpipe 100. Moreover, the operating member 108 is normally biased by the weight of the hose 102 and against the counterbalancing spring 110 in the counterclockwise direction, as viewed in Fig. 1, in order to insure that the midsection of the hose 102 is moved into its lower position normally to rest upon the guide elements 107. When the solenoid device 112 is energized, the armature 113 is at-

tracted rotating through the coil spring 114 the operating member 108 in the clockwise direction, as viewed in Fig. 1, about the pivot pin 109 with the bias of the coil spring 110 so that the operating member 108 lifts or elevates the midsection of the hose 102 from its lower position into its upper position, whereby the drain mechanism 105 is operated from its draining position into its non-draining position. Subsequently, when the solenoid device 112 is de-energized the weight of the hose 102 returns the operating member 108 in the counterclockwise direction, as viewed in Fig. 1, back into its normal position against the bias of the counterbalancing spring 110 so that the midsection of the hose 102 is returned to its lower position in order again to return the drain mechanism from its non-draining position into its draining position.

The construction of the drain mechanism 105 has not been shown in great detail, since it forms no part of the present invention, and is disclosed in the copending application of Edgar S. Stoddard, Serial No. 86,291, filed April 8, 1949.

Mounted within the lower portion of the vat 27 above the bottom wall 29 and below the movable rack structure 64 and surrounding the impeller 90 is a suitable electric heater 120 which is preferably of the sheathed resistance conductor type; which heater 120 is employed for the purpose of drying the dishes after they have been washed and rinsed as explained more fully hereinafter. The opposite terminal ends of the heater 120 extend through liquid-tight openings provided in the bottom wall 29 to the exterior so that electrical connections may be made thereto exteriorly of the vat 27. Also, a timer, not shown, is arranged in the upper portion of the space disposed between the left-hand side wall 14 of the cabinet 11 and the left-hand side wall 30 of the vat 27; which timer is provided with an operating shaft, not shown, that extends through aligned openings provided in the front wall 17 and in the front panel 23, the extreme outer end of the operating shaft removably carrying a control knob 121, the control knob 121 cooperating with a substantially annular trim and indexing plate 122 carried by the front panel 23. Specifically, the control knob 121 carries an index pointer 123 that cooperates with the legends "off" and "on" provided on the indexing plate 122. Also, a terminal board, not shown, is disposed in the lower portion of the space mentioned below the timer; which terminal board carries a measuring coil or relay, not shown, and other wiring, completing the electrical connections involving the operating motor 91, the heater 120, the solenoids 99 and 112, and the timer, not shown.

The construction and arrangements of the timer and the electrical wiring of the apparatus 10 have not been illustrated in detail, as they form no part of the present invention, and are disclosed in the copending application of Douglas F. Illian, Serial No. 91,906, filed May 7, 1949, now Patent No. 2,624,353, dated Jan. 6, 1953.

In the operation of the apparatus 10, washing liquid is sprayed from the spraying device 96 downwardly into the vat 27 and is circulated upwardly by the impeller 90 through the vat 27 in order to effect washing of the dishes supported therein; and thereafter the supported dishes are dried by a blast of hot air produced by the heater 120 and circulated by the impeller 90 in the vat 27. During the operation of the apparatus 10, the door 42 occupies its closed position so that

the marginal rim 41 carried by the marginal flange 46 of the inner body sheet 45 engages the adjacent front surface of the vat rib 40 in order to limit the direct admission of liquid from the vat 27 into the doorway 33. Also, the baffles 79 and 80 carried by the respective side walls 30 and 31 of the vat 27 are effective in deflecting liquid from the doorway 33. Further, the baffle 12 co-operating with the vat rib 40 defines the pocket 78 therebetween, as previously explained, which pocket 78 appears to create turbulence of the liquid adjacent to the entrance to the doorway 33 in order further to limit the admission of liquid thereto. The exact mode of cooperation between the baffle 12 and the vat rib 40 and the action in the pocket 78 is not altogether understood, but, as previously noted, it is believed that the limiting of the entrance of the liquid into the doorway 33 by this arrangement is brought about fundamentally by the turbulence or curtain action that is produced upon the liquid in the pocket 78. In any case, the arrangement described is very effective to limit the entrance of liquid into the doorway 33. Finally, the small amount of liquid that does enter the doorway 33 has no substantial momentum and falls downwardly between the flanges of the doorway 33 and the marginal flange 44 of the outer body sheet 43 rearwardly of the ledge 37, whereby this liquid is returned via the groove 39 into the sump 38 to be recirculated by the bladed impeller 90.

In any case, the arrangement of the gasketless-door construction described above is very effective to prevent the escape of liquid from the vat 27. Moreover, the arrangement is very advantageous in view of the fact that the desired action is obtained notwithstanding the inward spacing of the baffle 12 from the vat rib 40, whereby there is no shearing or scraping between these two elements and so that exact fits of these two elements are unnecessary, and movements of the door 42 between its open and closed positions take place without any interference or noises.

In view of the foregoing, it will be understood that there has been provided dishwashing apparatus of the front-opening gasketless-door type that comprises an improved arrangement of the baffles carried by the walls of the vat and by the door in order to prevent the escape of liquid from the vat and in order to allow free movements of the door between its open and closed positions without shearing or scraping actions between the cooperating baffles.

While there has been described what is at present considered to be the preferred embodiment of the invention, it will be understood that various modifications may be made therein, and it is intended to cover in the appended claims all such modifications that fall within the true spirit and scope of the invention.

What is claimed is:

1. In washing apparatus including a vat adapted to contain washing liquid and provided with top and bottom walls and opposed side walls terminating in an upstanding forwardly directed doorway, said doorway having top and bottom flanges and opposed side flanges, said flanges terminating in an upstanding front opening, an upstanding inverted substantially U-shaped rib formed in said top and side walls at the junction thereof with said top and side flanges and inwardly disposed with respect to said top and side walls, said bottom flange be-

ing disposed below the ends of the legs of said rib and provided with an upwardly directed ledge extending between said side flanges and terminating adjacent to said front opening, a front door, and hinge mechanism mounting said front door within said doorway with the bottom of said front door in straddling relation with said ledge, said front door being movable between a substantially horizontal open position and a substantially vertical closed position with respect to said front opening, the inside of said front door carrying an inverted substantially U-shaped outwardly directed rim engaging said rib when said front door occupies its closed position in order to limit the admission of the washing liquid into said doorway; the combination comprising an inverted substantially U-shaped baffle carried by the inside of said front door adjacent to said rim, said baffle being spaced radially inwardly with respect to said rim and projecting rearwardly with respect thereto into the area defined by said rib in inwardly spaced relation therewith toward the interior of said vat when said front door occupies its closed position, said baffle cooperating with said rib when said front door occupies its closed position to define an inverted substantially U-shaped pocket therebetween, said pocket also being substantially U-shaped in cross section and causing a turbulency of the washing liquid therein in order further to limit the admission of the washing liquid into said doorway.

2. In washing apparatus including a vat adapted to contain washing liquid and provided with top and bottom walls and opposed side walls terminating in an upstanding forwardly directed doorway, said doorway having top and bottom flanges and opposed side flanges, said flanges terminating in an upstanding front opening, an upstanding inverted substantially U-shaped rib formed in said top and side walls at the junction thereof with said top and side flanges and inwardly disposed with respect to said top and side walls, said bottom flange being disposed below the ends of the legs of said rib and provided with an upwardly directed ledge extending between said side flanges and terminating adjacent to said front opening, a front door, and hinge mechanism mounting said front door within said doorway with the bottom of said front door in straddling relation with said ledge, said front door being movable between a substantially horizontal open position and a substantially vertical closed position with respect to said front opening, said front door having a cavity in the inside thereof bounded by top and opposed side flanges, said door flanges cooperating with said doorway flanges and the rear edges of said door flanges cooperating with said rib when said front door occupies its closed position in order to limit the admission of the washing liquid into said doorway; the combination comprising an inverted substantially U-shaped baffle carried by said front door within said cavity, said baffle also being substantially Z-shaped in cross section including connected outer and inner walls, said outer baffle wall being secured upon the inside of said door flanges and said inner baffle wall projecting rearwardly beyond the rear edges of said door flanges, said inner baffle wall also being spaced radially inwardly with respect to said rib and projecting into the area defined by said rib toward the interior of said vat when said front door occupies its closed position.

11

3. In washing apparatus including a vat adapted to contain washing liquid and provided with top and bottom walls and opposed side walls terminating in an upstanding forwardly directed doorway, said doorway having top and bottom flanges and opposed side flanges, said flanges terminating in an upstanding front opening, an upstanding inverted substantially U-shaped rib formed in said top and side walls at the junction thereof with said top and side flanges and inwardly disposed with respect to said top and side walls, said bottom flange being disposed below the ends of the legs of said rib and provided with an upwardly directed ledge extending between said side flanges and terminating adjacent to said front opening, a front door provided with an inner body sheet having an inverted substantially U-shaped rearwardly directed marginal flange and an outer body sheet having an inverted substantially U-shaped rearwardly directed marginal flange and secured together in nested spaced-apart relation, and hinge mechanism mounting said front door within said doorway for movements between a substantially horizontal open position and a substantially vertical closed position with respect to said front opening, the lower ends of said body sheets being arranged in straddling relation with said ledge, the rear edges of the marginal flange of said inner body sheet co-operating with said rib when said front door

occupies its closed position in order to limit the admission of the washing liquid into said doorway; the combination comprising an inverted substantially U-shaped baffle carried by said front door within said inner body sheet, said baffle also being substantially Z-shaped in cross section including connected outer and inner walls, said outer baffle wall being secured upon the inside of the marginal flange of said inner body sheet and said inner baffle wall projecting rearwardly beyond the rear edges of the marginal flanges of said body sheets, said inner baffle wall also being spaced radially inwardly with respect to said rib and projecting into the area defined by said rib toward the interior of said vat when said front door occupies its closed position.

FRANK D. LOW.
